US00D582413S

(12) **United States Design Patent**
Parker et al.

(10) **Patent No.:** US D582,413 S
(45) **Date of Patent:** ** Dec. 9, 2008

(54) **RADIO FREQUENCY IDENTIFICATION
DEVICE CASE**

(75) Inventors: **Brian G. Parker**, Alto, MI (US); **Paul J. Rugg**, Grandville, MI (US)

(73) Assignee: **Cascade Engineering, Inc.**, Grand Rapids, MI (US)

(**) Term: **14 Years**

(21) Appl. No.: **29/298,897**

(22) Filed: **Dec. 14, 2007**

(51) **LOC (8) Cl.** 14-02

(52) **U.S. Cl.** D14/383

(58) **Field of Classification Search** D14/383-387, D14/426, 422; 345/169, 173; 356/71, 237.1; 382/116, 124-126, 181, 207; 235/382, 382.5; 355/64, 65, 75, 81; 118/31.5; 283/68-70, 283/74, 75, 78; 700/218

See application file for complete search history.

(57) **CLAIM**

The ornamental design for radio frequency identification device case, as shown and described.

DESCRIPTION

FIG. 1 is a perspective view of the current embodiment of the radio frequency identification device case;

FIG. 2 is front view thereof;

FIG. 3 is a rear view thereof;

FIG. 4 is a side view thereof (both side views being mirror images of each other); and,

FIG. 5 is an end view thereof (both end views being mirror images of each other).
